UNITED STATES PATENT OFFICE.

JOHN ROY STOGNER, OF LANCASTER, SOUTH CAROLINA.

ICE-HOOK.

1,401,008.

Specification of Letters Patent. Patented Dec. 20, 1921.

Application filed October 8, 1920. Serial No. 415,681.

To all whom it may concern:

Be it known that I, JOHN ROY STOGNER, a citizen of the United States, residing at Lancaster, in the county of Lancaster and State of South Carolina, have invented new and useful Improvements in Ice-Hooks, of which the following is a specification.

My present invention has reference to an ice tong.

10 My primary object is to produce an implement of this character which shall be of a foldable nature so that the same can be conveniently carried either in the hand or in the pocket of the owner without danger 15 of inflicting injury to the owner or to the owner's clothes, and also one which, when in set up position is adjustable for engaging varying sizes of blocks of ice and is effectively braced in its last mentioned position 20 to positively withstand any strain to which it may be subjected.

A further object is the production of a collapsible ice hook which shall be of a simple nature, cheaply manufactured, and 25 readily set up in engaging position and quickly and easily collapsed when being conveyed and when not required for use.

The foregoing, and other objects which will appear as the nature of the invention 30 is better understood, may be accomplished by a construction, combination and operative assemblage of parts, such as is disclosed by the drawings which accompany and which form part of this application.

35 In the drawings:—

Figure 1 is a front elevation showing the hook in its folded condition.

Fig. 2 is a similar view showing the hook in its spread or operative position.

40 Fig. 3 is a sectional view approximately on the line 3—3 of Fig. 2.

Fig. 4 is a sectional view approximately on the line 4—4 of Fig. 2.

Referring now to the drawings in detail, 45 two oppositely arranged comparatively short plates, 1, respectively, are connected, adjacent to their ends by pivots 2. These pivots also pass through arched or curved upper portions of arms 3. The arms 3 are 50 preferably in the nature of cross sectionally round rods. The straight lower ends of the arms 3 have secured to their opposite sides comparatively short plates 4. These plates project inwardly of the arms and form 55 therebetween pockets. In the pockets of each pair of plates there is pivoted, adja-

cent the upper and inner corners of the said plates 4, the arm portions of hooks 5. The hooks are, of course, designed to engage with the blocks of ice, and the pivotal connection between the hooks and the pockets is such as to permit of the said hooks being swung to bring the beaks thereof against the inner edges of the arms 3. Also the plates that constitute the pockets are designed to exert a pressure against each other so as to bind against the opposite sides of the arm portions of the hooks and thus effectively retain the same in parallelism with the arms. 60 65 70

The numeral 6 designates the handle of the device. The handle is in the nature of a U-shaped bail and is centrally formed with a depending shank 7 that passes between the plates 1 and the ends of the arms, 3. 75 The shank is constructed of two sections, the said sections at the sides of their confronting ends being preferably reduced and in these reduced portions there are arranged links 8 that are pivoted, as at 9 to 80 the respective sections of the shank. This, it will be noted, provides a hinged joint between the shank sections. The lower section of the shank, which is indicated for distinction by the numeral 10 has a laterally 85 extending head portion at the free end thereof. This head is indicated by the numeral 11, and passing through openings in the ends of the said head are pivots 12. Each of the pivots secures to the head a 90 link 13. The links are, of course, directed oppositely from the head and from the shank and each of the said links is pivoted, as at 14 to one of the arms 3. 95

When the device is in operative position, 100 the handle 6 will rest against the upper edges of the plates 1. The links 13 are arranged at an angle with respect to the arms 3, and the arms of the hooks are swung through the pockets 4 in alinement with the 105 arms 3. The upward pull on the handle 6 will draw the shank upwardly between the plates 1, moving the links 13 to close the arms and hooks. The greater the pull upon the handle, the nearer the hooks are brought 110 together, and when a block of ice is engaged by the hooks, the links 13 are disposed at an upward angle between the arms 3. When the device is to be collapsed, as when not required for use or when designed to be conveyed either in the hand or pocket of the owner, the shank is moved outwardly 115

between the plates 1, and this causes the arms 3 to be drawn toward each other. The hooks are swung upon their pivots outward of their respective pockets, so that the beaks thereof are brought against or between the arms. The outer section of the shank which carries the handle is then swung upon its hinged connection to bring the handle against the folded arms, links and hooks.

10 Having described, the invention, what I claim, is—

15 1. In an ice tongs, a handle having a shank constructed of sections which are hingedly connected, plates disposed over the opposite faces of the shank, arms pivoted between the plates adjacent to the edges of the shank, pivoted links between the end of the shank and the arms, pockets on the inner face of the arms at the free ends thereof, and hooks having arm members designed to be received in the pockets and pivoted therein.

20 2. In an ice tongs, a handle having a shank constructed of sections which are hingedly connected, plates disposed over the opposite faces of the shank, arms pivoted

25 between the plates adjacent to the edges of the shank, pivoted links between the end of the shank and the arms, pockets on the inner face of the arms at the free ends thereof, and hooks having arm members designed to be received in the pockets and pivoted therein, said pockets comprising spring plates which exert a tension toward each other whereby, when the arms of the 30 hooks are arranged therebetween to bind thereagainst and hold the same in alinement with the first mentioned arms.

3. A device of the class described comprising a pair of curved arms, a pair of 40 relatively short plates pivotally secured to one end of said arms, plates secured to the opposite ends of said arms, hooks pivotally secured to said plates, a handle having a sectional shank extending between the first 45 mentioned plates and provided with a laterally extending head, and a pair of links pivotally secured to said arms and to the head of said sectional shank.

40 In testimony whereof I affix my signature.

JOHN ROY STOGNER.
